US00D942190S

(12) **United States Design Patent** (10) **Patent No.:** **US D942,190 S**
Li et al. (45) **Date of Patent:** **** Feb. 1, 2022**

(54) **SUPPORT**

(71) Applicant: **SHENZHEN SENSETIME TECHNOLOGY CO., LTD.**, Shenzhen (CN)

(72) Inventors: **Cheng Li**, Shenzhen (CN); **Dingbo Liu**, Shenzhen (CN)

(73) Assignee: **SHENZHEN SENSETIME TECHNOLOGY CO., LTD.**, Guangdong (CN)

(**) Term: **15 Years**

(21) Appl. No.: **29/732,681**

(22) Filed: **Apr. 27, 2020**

(30) **Foreign Application Priority Data**

Nov. 5, 2019 (CN) 201930606557.3

(51) **LOC (13) Cl.** **20-02**

(52) **U.S. Cl.**

USPC **D6/681**

(58) **Field of Classification Search**

USPC D6/672, 673, 681, 681.1, 681.2, 681.3,

D6/682, 682.3, 682.5, 512, 513, 515, 542;

D14/217, 224, 229, 239

CPC A47F 1/00; A47F 1/04; A47F 1/08; A47F

5/0031; A47F 5/01; A47K 5/00; A47G

29/00; A47G 29/08

See application file for complete search history.

(57) **CLAIM**

The ornamental design for a support, as shown and described.

DESCRIPTION

FIG. 1 is a front view of a support showing the new design; FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a top, right side perspective view thereof;

The broken lines depict portions of the article that form no part of the claimed design.

1 Claim, 7 Drawing Sheets
